ROTARY PLAY EXERCISER FOR A PET ANIMAL

Bernard Suchowski, Marlboro, David D. Lovitz, Short Hills, and Claud W. Kissin, Fort Lee, N.J., assignors to The Hartz Mountain Corporation, Harrison, N.J.

Filed Jan. 30, 1975, Ser. No. 545,367

Term of patent 14 years

Int. Cl. D30—07

U.S. Cl. D30—42

FIG. 1

FIG. 2

FIG. 3

FIG. 4

FIG. 5

FIG. 6

FIG. 1 is a front elevational view of a rotary play exerciser for a pet animal showing our new design;

FIG. 2 is a right side elevational view;

FIG. 3 is a top plan view;

FIG. 4 is a rear elevational view;

FIG. 5 is a left side elevational view; and

FIG. 6 is a bottom plan view.

We claim:

The ornamental design for a rotary play exerciser for a pet animal, as shown.
